By his attorney Frank P. Wentworth

UNITED STATES PATENT OFFICE.

HENRY B. THOMPSON, OF NEW YORK, N. Y., ASSIGNOR TO LYDIA B. KOCH, OF NEW YORK, N. Y.

CINEMATOGRAPHIC TARGET.

1,308,876.

Specification of Letters Patent.

Patented July 8, 1919.

Application filed October 17, 1917. Serial No. 196,994.

To all whom it may concern:

Be it known that I, HENRY B. THOMPSON, a citizen of the United States, residing at the borough of Manhattan, city, county, and State of New York, have invented certain new and useful Improvements in Cinemato-graphic Targets, of which the following is a specification, reference being had therein to the accompanying drawings, which form a part thereof.

My invention relates to cinematographic targets and more particularly to improvements in that portion of the target structure, the operations of which facilitate marking the efficiency of a marksman.

In a target made in accordance with my invention, the screen, as in other targets of this character, consists of a continuous strip or web of paper, or other light impenetratable material, the feeding and guiding means for which strip or web are so arranged and constructed as to insure that portion thereof upon which an image is projected, remaining at all times perfectly taut, this strip or web being rewound as it is being fed through the machine. This feeding mechanism is so constructed as to insure a uniform tension upon this strip or web at the sight opening of the target irrespective of variance in the dimensions of the rewinding wheels.

A further characteristic of my invention is a simplification of the back plate or shield structure to facilitate the adjustment of the individual plates of this structure, to render them more or less sensitive as desired to the force exerted by the impact of a bullet therewith.

I also provide in conjunction with said back plate or shield structure, a make and break mechanism in the circuit controlling the projector and other mechanisms in the apparatus, which will be substantially instantly actuated by the movement of any of the plates of the back plate or shield structure, and which will not be subjected to substantial deterioration by reason of sparking.

A target made in accordance with my invention is capable of operation with absolute reliability and with a rapidity commensurate with those severe tests to which a target is subjected when a number of marksmen are utilizing same.

The make and break mechanism is so constructed as to not only be operative with

very slight movement of any plate of the back plate or shield structure, but to store the energy applied thereto by the plate in a manner to permit the utilization of a portion of this make and break mechanism for restoring the plate to normal prior to the restoration of the circuit to normal. This limitation in the quantity of movement required for actuating the make and break mechanism permits simplicity in the structure of the operative connections between each plate and the make and break mechanism associated therewith, it being essential that each plate have associated therewith its own make and break mechanism.

The make and break mechanisms are so arranged as to very much simplify the wiring of the target with a consequent reduction in likelihood of such a disarrangement of parts as would tend to interfere with the continued operation of the target, while in the event of such a disarrangement, the trouble may be readily located and quickly remedied.

The entire structure of the target is such as to permit its production with a minimum of specially formed and shaped parts, thus permitting economy in the construction of the target.

I so construct the target that the opening of the front frame through which the screen is presented, may be elevated to the desired height while adequate protection from stray shots, will be afforded the working parts of the target structure.

The invention consists in the novel features of construction and combination of parts, hereinafter set forth and described and more particularly pointed out in the claims hereto appended.

Referring to the drawings:

Figure 1 is a side view partly in section and partly in elevation of a target structure embodying my invention;

Fig. 2 is a rear view of one of the plates and the make and break mechanism associated therewith;

Fig. 3 is a sectional view of a portion of the mechanism shown in Fig. 2; and

Fig. 4 is a detail view in elevation of the mount for the back plate.

Like letters refer to like parts throughout the several views.

In the embodiment of my invention shown in the drawings, the main frame is composed

of vertical bars a connected by suitable horizontal cross bars to impart the desired rigidity to the structure. Carried by this frame is a deep frame b located at the front 5 of the target structure and having therein a sight opening of the desired dimensions through which the screen is exposed. Connected with the vertical bars a adjacent the top thereof are cross bars a' braced by corner plates a^2 , while toward the bottom of the frame are cross bars a^3 extending parallel with the bars a' . Suitably supported from the bars a are bearings for a reel c containing the paper strip or web d . 10 The strip or web d in passing from the reel c is passed about the guide roller e , below the frame b , over and around the roller e' carried by the cross bar a' above the frame b , and about the rollers e^2-e^3 , the 15 former of which is closely adjacent the roller e' and the latter of which is adjacent the roller e , thus positioning two parallel reaches of the strip or web d closely adjacent and rearwardly of the sight opening 20 in the frame b . The rollers $e-e^3$ and $e'-e^2$ are so positioned in relation to each other to bring the two reaches of said strip or web practically into engagement with each other so as to insure accuracy in the register of 25 the openings formed by the passage of a bullet through said reaches. 30

The roller e^2 is mounted between corresponding plates a^2 upon opposite sides of the machine, while the roller e^3 is mounted 35 upon the cross bars a^3 . After leaving the roller e^3 , the strip or web d passes about a roller f mounted upon the bars a^3 upwardly and around a roller f' mounted upon the braces a' and downwardly to a pair of 40 presser rollers g and g' mounted in suitable bearings upon cross bars a^4 below and parallel to the cross bar a^3 . One of the rollers $g-g'$ is adjustable with relation to the other to regulate the pressure exerted by said 45 rollers upon the strip or web d , suitable means actuated by the handle g^2 being provided to permit the regulation of this pressure.

After leaving the roller g' , the paper strip or web passes to a rewinding reel h , said rewinding reel being driven in any desired manner as by being belted to one of the rollers $g-g'$, the character of this drive being such as to permit slippage to compensate 55 for the gradual increase in the diameter of the roller as the web is gradually rewound.

In the embodiment of the invention shown, the presser rollers $g-g'$ are constantly rotated by means of a motor i and a speed reducing mechanism illustrated conventionally at j , said mechanism being operatively connected to the motor and to one of the presser rollers as g . This construction is essential since the rate of lineal 60 traverse of the web must be very slow, the 65

amount of movement required to close a bullet hole in the two reaches of the strip or web extending across the sight opening in the frame b being only about an eighth of an inch, by reason of the fact that these two reaches move simultaneously in opposite directions.

By running the strip or web d between the presser rollers $g-g'$, I not only secure feeding movement of the strip at a uniform speed but flatten the paper or other material of the web or strip in a manner to permit it to roll fairly flat upon the reel h . I have found, however, that the jagged opening formed upon the passage of a bullet through the paper precludes any possibility of it being rolled tightly upon the reel h , although in the event of the roll thereon becoming too large before the strip or web upon the reel c has been exhausted, the reel h may be removed and another reel substituted therefor. The freedom from obstruction of the frame b adjacent the lower part thereof facilitates the mounting and removal of the reels c and h .

The lower cross bars of the frame are provided with an extension k extending forwardly of the frame b and connected with the forward uprights a by inclined bars k' terminating in a horizontal section k^2 in which the bearings for the reel c are formed. By this construction, the bars k' may be used as skids in positioning the reel of paper web or strip in relation to the target.

The portion of the target structure below the frame b is closed by means of an inclined shield l which ordinarily will protect the motor, the supply reel, the rewinding reel, the presser mechanism and the speed box from stray bullets fired at the target.

Suitable lighting fixtures b' are arranged rearwardly of the frame b so that light rays may escape through registering openings in the two reaches of the frame b adjacent and rearwardly of said frame.

Adjacent the rear of the frame work of the target structure, is a back plate structure comprising a series of overlapping plates m stepped in relation to each other, said plates being mounted, so as to be normally balanced or slightly overbalanced toward the frame b and pivotally supported so as to oscillate freely under the force of the impact of a bullet therewith. Each of the plates m extends transversely of the frame structure, the opposite sides thereof terminating beyond the sight opening in the frame b thus permitting the pivotal supporting means to be positioned without the range of bullets passing through the screen.

The various plates m are supported from upwardly inclined angle bars n upon opposite sides of the machine, one flange of said angle bars being presented toward the frame.

b. Each of the plates m is provided with angle bar legs m' adjacent opposite sides of the plate, the rearwardly extending flange of said bars, being pivotally connected with 5 a screw m^2 adjustably mounted in a flange of the bar n . Said screw is provided with lock nuts m^3-m^4 acting upon opposite sides of said flange, so as to hold said screw in any adjusted position. The end of each screw 10 is slotted, and straddles the flange of the leg m' pivotally connected therewith. By having the slot at the end of the screw m^2 of the proper depth, and having said screw project at an upward angle, the oscillatory 15 movement of the plate supported by the screw, toward the frame b , is limited.

Each of the plates m is provided with suitable laterally extending stiffening bars m^5 to avoid a possible flexure of said plates 20 under the force of the impact of a bullet therewith, thus permitting the use of light plates.

The electrical circuit by means of which the operative effect of the projector is determined, is controlled by the movement of any 25 of the plates m under the force of the impact of a bullet therewith.

In the embodiment of the invention shown, I utilize the movement of the several 30 plates m for controlling this circuit, by a structure embodying therein a channel beam o extending substantially parallel with and between the bars n . This channel beam is provided with a plate of suitable insulating 35 material o' , and is closed by a back plate o^2 . Carried by said insulating plate o' are a plurality of make and break mechanisms, one such mechanism being positioned rearwardly of each plate m . A description of 40 but one of the make and break mechanisms is necessary.

Carried by the insulating plate o' is a fixed contact member p positioned adjacent an opening o^3 through the bottom of the 45 channel member o and the insulating plate o' . Mounted upon said plate o' adjacent said opening o^3 and projecting across same, is a spring contact member p' , the strength of this spring being sufficiently great to 50 restore the back plate m to normal, after said back plate has been displaced by the impact of a bullet thereupon. Said spring member is provided with an adjustable point contact p^2 which may, if desired, be 55 provided with a platinum tip to prevent corrosion thereof or burning from the spark. The contact member p is also provided with a non-corrosive area coöperating with the contact p^2 .

60 Each of the fixed contact members p is placed in electrical connection with the movable member p' of the adjoining make and break mechanism, by means of a suitable conductor, such as q , so that the various make and break mechanisms are ar-

ranged in electrical series, it being essential that all of the mechanisms be so set as to provide a normally closed circuit, the interruption of which circuit will have the desired operative effect upon the projector, 70 and other mechanisms of a target apparatus, controlled thereby. The first and the last make and break mechanisms of this series, are electrically connected with the terminals 75 from any desired source of electrical supply.

Each of the plates m is provided with a thrust member r adapted to project through the opening o^3 adjacent said plate and operatively engage the spring member p' of the make and break mechanism associated 80 with said plate. To avoid short circuiting of the apparatus through the frame of the machine, I form this thrust member of a block r of insulating material, carried by the plate m , a metallic section r' secured 85 to said insulating block and a bearing point r^2 of insulating material normally in operative connection with the said spring contact member p' . By connecting the metallic section r' with the insulating block r by 90 means of screw threads, slight adjustment of the insulating bearing member r^2 with relation to the spring contact member p' may be secured, although the adjustability of the contact p^2 may permit the setting of 95 the switch, or its regulation, to accord with any variance in the position of the plate m .

The operation of the herein described device is substantially as follows:

When a target made in accordance with 100 my invention is in use, the motor i is continuously operated, thus driving the presser rollers $g-g'$ at a continuous, uniform speed. This speed, however, is very low so as to impart a very slow traverse to the web or strip 105 d , the speed box j insuring the desired reduction of speed in said presser rollers, as compared with that of the motor i . As the web passes from the roller g' it is gradually rewound upon the reel h thus affording storage 110 of the used paper web or strip in a convenient manner to facilitate its removal from the machine and its return to the mill as scrap. The rollers $g-g'$ keep that portion 115 of the paper strip or web between them and the reel h perfectly taut and will also flatten the paper somewhat about the jagged openings therein, to facilitate its rewinding upon the reel h .

When a fire arm is discharged at the 120 target, the bullet passes through both parallel reaches of the paper strip or web d exposed through the sight opening of the frame b , leaving registering openings in said reaches through which light rays from 125 the lamps in the fittings b' reflected by the back reaches of the web pass, thus penetrating the screen when struck by the bullet and permitting accuracy in marking.

After the bullet passes through the paper 130

web or strip d , it strikes one of the plates m of the back plate or shield structure with sufficient force to oscillate said plate toward the channel beam o . By reason of the construction and arrangement described, the bullet must strike some one of these plates, and the entire energy of the bullet will therefore be expended in physically displacing the plate, since the plates themselves possess sufficient rigidity to avoid flexure or distortion from the force of the impact.

As a plate m moves toward the channel bar o , the thrust mechanism carried thereby will flex the spring contact member p' and thus separate the point p^2 thereof, from the fixed contact member p carried by the insulating plate o' , interrupting the circuit and setting in motion other mechanisms which have the effect of stopping the projector substantially simultaneously with the passage of the bullet through the screen. The mechanisms for effecting this stoppage of the projector are immaterial to the present invention as any well known mechanism may be employed for this purpose.

The accumulated energy resulting from the impact of a bullet with a plate m , and the movement of the plate thereunder, after it leaves the vertical center meets resistance from the spring contact p' and sufficient of this energy is stored in this spring to insure the restoration of the plate m to normal after a brief interval.

By utilizing a normally closed electrical circuit having therein, in series, a sequence of make and break mechanisms the wiring of the apparatus is not only very much simplified, but reliability in the actuation of the controlling mechanism for the projector, is secured.

The manner of mounting the several plates m permits great nicety in the adjustment of these plates by a very simple mechanism which not only serves to pivotally support the plates, but also to define the limit of their movement toward the frame b . The adjustment of the plates to secure the desired balanced or overbalanced condition thereof, is effected by merely moving the point of pivotal support of the plates toward or away from the frame b by means of the screws m^2 pivotally connected with the respective legs m' of the plates.

In the event of a failure of the mechanism to properly respond to an impact of a bullet with the back plate structure, inspection of the make and break mechanism and of the means for determining the normal position of each of the plates, may be conveniently had from the back of the target structure and any readjustment of the electrical contacts, or the pivotal supports for the several plates, may be readily effected. The electrical

wiring is such that vibration in the apparatus will have little or no tendency to disturb the electrical conditions.

The quantity of movement between the lower end of the legs m' and the slotted screws m^2 in which they are pivotally mounted, is such as to minimize any tendency for a plate to rebound when restored to normal by a spring contact member p' .

As heretofore stated the weight of the plates may be very much reduced by using back braces such as m^5 , thus increasing the sensitiveness of these back plates by reason of the lessening of the load which must be neutralized or overcome by the force of the impact of a bullet therewith.

In targets made in accordance with my invention, it is customary to use small caliber fire arms and light charges of ammunition, the purpose of the target primarily being to familiarize marksmen with fire arms and with firing at moving targets. The use of such targets with long range practice is not feasible. A target of this character must therefore be adapted for use at short ranges and with fire arms developing low velocity in the missile. These characteristics are present in the target herein shown and described.

It is not my intention to limit the invention, to the precise details of construction shown in the accompanying drawings, it being apparent that such may be varied without departing from the spirit and scope of the invention.

Having described what I claim as new and desire to have protected by Letters Patent is:

1. A cinematographic target embodying therein a frame having a sight opening therein, means adapted to support a reel of paper strip or web adjacent said frame, guide rollers adapted to conduct said paper strip or web in closely adjacent parallel reaches across the sight opening in said frame, a pair of presser rollers, guiding means for said paper strip or web between the parallel reaches thereof and said presser rollers, a rewinding reel, means simultaneously actuating said presser rollers and said rewinding reel, and a back plate structure rearwardly of said parallel reaches.

2. A cinematographic target embodying therein a frame having a sight opening therein, means adapted to support a reel of paper strip or web below said frame, a guide roller between said reel and below said frame, a guide roller above said frame around which the paper strip or web may pass, a guide roller below said last named roller about which the paper strip or web may pass, a guide roller below said frame whereby two closely adjacent parallel reaches of said strip or web are positioned across the sight opening in said frame, presser rollers, guide

rollers below and above said frame about which the strip or web may pass to said presser rollers, a rewinding reel, means simultaneously actuating said presser rollers and said rewinding reel, and a back plate structure rearwardly of said parallel reaches.

3. A cinematographic target embodying therein a frame having a sight opening 10 therein, means adapted to support a reel of paper strip or web below said frame, a guide roller between said reel and below said frame, a guide roller above said frame around which the paper strip or web may 15 pass, a guide roller below said last named roller about which the paper strip or web may pass, a guide roller below said frame whereby two closely adjacent parallel reaches of said strip or web are positioned across 20 the sight opening in said frame, presser rollers, guide rollers below and above said frame about which the strip or web may pass to said presser rollers, a rewinding reel, a continuously rotating motor, connections between 25 said motor and said presser rollers whereby said rollers are continuously rotated at very low, uniform speed, connections between said presser rollers and said rewinding reel, and a back plate structure 30 rearwardly of said parallel reaches.

4. A cinematographic target embodying therein a frame having a sight opening therein, a movable, light impenetratable, frangible, screen, means adapted to impart movement to said screen, a back plate or shield embodying therein a plurality of independently movable, overlapping, oscillatory plates, pivotal supports for each of said plates, means adjacent said pivotal supports 40 limiting the oscillatory movement of the plate, and an electric circuit including therein a plurality of make and break mechanisms, each associated with a back plate, and adapted to be actuated substantially simultaneously with the movement of its associated back plate after the impact of a bullet thereupon.

5. A cinematographic target embodying therein a frame having a sight opening 50 therein, a movable, light impenetratable, frangible, screen, means adapted to impart movement to said screen, a back plate or shield embodying therein a plurality of independently movable overlapping, oscillatory plates, adjustable members movable toward and from the screen, pivotal connections between each of said plates and coöperating adjustable members whereby said plates may be set by varying the position of 55 its pivotal supporting means with relation to the screw, and an electric circuit including therein a plurality of make and break mechanisms, each associated with a back plate, and adapted to be actuated substantially simultaneously with the movement of 60

its associated back plate after the impact of a bullet thereupon.

6. A cinematographic target embodying therein a frame having a sight opening therein, a movable, light impenetratable, 70 frangible, screen, means adapted to impart movement to said screen, a back plate or shield embodying therein a plurality of independently movable, overlapping, oscillatory plates, inclined bars adjacent opposite 75 sides of the target, adjustable slotted screws, carried by said bars, legs upon the opposite sides of each of said plates adapted to enter the slot in said screws, and pivotal connections between each of said screws and the 80 target leg coöperating therewith, whereby said plate may be set by movement of said screws toward or from said screw, and the bottom of the slot in said screw will limit the oscillatory movement of said plate. 85

7. A cinematographic target embodying therein a frame having a sight opening therein, a movable, light impenetratable, frangible, screen, means adapted to impart movement to said screen, a back plate or 90 shield embodying therein a plurality of independently movable, overlapping, oscillatory plates, pivotal supports for each of said plates, means limiting the oscillatory movement of said plates respectively, and 95 means whereby a projector will be stopped substantially simultaneously with the impact of a bullet with any of said plates, comprising a normally closed, electrical circuit containing therein, in series, a sequence of 100 make and break mechanisms, adjacent said plates respectively, and means carried by each of said plates adapted to operatively engage its coöperating make and break mechanism. 105

8. A cinematographic target embodying therein a frame having a sight opening therein, a movable, light impenetratable, frangible, screen, means adapted to impart movement to said screen, a back plate or 110 shield embodying therein a plurality of independently movable, overlapping oscillatory plates, pivotal supports for each of said plates, means limiting the oscillatory movement of said plates respectively, a support, 115 insulating material carried thereby, said beam and said material having an opening therethrough, and means operative substantially simultaneously with the impact of a bullet upon any of said plates, comprising a 120 normally closed electrical circuit containing therein, in series, a sequence of make and break mechanisms adjacent said plates respectively, consisting of a fixed electrical contact carried by said insulating material 125 adjacent each opening therethrough, a spring contact carried by said material normally engaging its opposed fixed contact, and in constant electrical connection with the fixed contact of the adjacent make and 130

break mechanism, and a thrust member carried by each plate, projecting through one of said openings, and operatively engaging a spring contact, whereby the movement of any plate will interrupt the circuit, and said spring contact after each actuation will substantially simultaneously restore its coöperating plate to normal, and close the circuit.

9. A cinematographic target embodying therein a frame having a sight opening therein, a movable, light impenetratable, frangible screen, means adapted to impart movement to said screen, a back plate or shield embodying therein a plurality of independently movable, overlapping oscillatory plates, pivotal supports for each of said plates, means limiting the oscillatory movement of said plates respectively, a support, insulating material carried thereby, said beam and said material having an opening therethrough, and means whereby a projector will be stopped substantially simultaneously with the impact of a bullet with any of said plates, comprising a normally closed electrical circuit containing therein, in series, a sequence of make and break mechanisms adjacent said plates respectively, consisting of a fixed electrical contact carried by said insulating material adjacent each opening therethrough, a spring contact carried by said material normally engaging its opposed fixed contact, and in constant electrical connection with the fixed contact of the adjacent make and break mechanism, said spring contacts, each having an adjustable point whereby the make and break mechanisms may be synchronized with adjustment of said plates, and a thrust member carried by each plate, projecting through one of said openings, and operatively engaging a spring contact, whereby the movement of any plate will interrupt the circuit, and said spring contact after each actuation will substantially simultaneously restore its coöperating plate to normal, and close the circuit.

10. A cinematographic target embodying therein a frame having a sight opening therein, a movable, light impenetratable, frangible screen, means adapted to impart movement to said screen, a back plate or shield embodying therein a plurality of independently movable, overlapping oscillatory plates, pivotal supports for each of said plates, adjustable means limiting the oscillatory movement of said plates re-

spectively, a support, insulating material carried thereby, said beam and said material having an opening therethrough, and means whereby a projector will be stopped substantially simultaneously with the impact of a bullet with any of said plates, comprising a normally closed electrical circuit containing therein, in series, a sequence of make and break mechanisms adjacent said plates respectively, consisting of a fixed electrical contact carried by said insulating material adjacent each opening therethrough, a spring contact carried by said material normally engaging its opposed fixed contact, and in constant electrical connection with the fixed contact of the adjacent make and break mechanism, said spring contacts, each having an adjustable point whereby the make and break mechanisms may be synchronized with adjustment of said plates, and a thrust member carried by each plate, projecting through one of said openings, and operatively engaging a spring contact, whereby the movement of any plate will interrupt the circuit, and said spring contact after each actuation will substantially simultaneously restore its coöperating plate to normal, and close the circuit.

11. A cinematographic target embodying therein an elevated frame having a sight opening therein, means adapted to support a reel of paper strip or web below said frame, guide rollers adapted to conduct said paper strip or web in closely adjacent parallel reaches across the sight opening in said frame, a pair of presser rollers below said guiding means for said paper strip or web between the parallel reaches thereof, and said presser rollers, a rewinding reel below said means simultaneously actuating said presser rollers and said rewinding reel, below said frame, a removable shield forwardly of and below said frame, whereby the various strip feeding mechanisms are protected from stray bullets, and a back plate structure rearwardly of said parallel reaches.

In witness whereof, I hereunto affix my signature in the presence of two subscribing witnesses, this 29th day of September 1917.

HENRY B. THOMPSON.
